APPARATUS FOR SEPARATING GOLD

Frank W. Brintnall, Detroit, Mich., assignor to
Ulysses S. Bratton, Jr., Detroit, Mich.

Application December 16, 1935, Serial No. 54,781

23 Claims. (Cl. 209—12)

This invention relates to improvements in apparatus for refining gold.

Among the objects of my invention are to provide an improved apparatus for reclaiming gold whereby the gold bearing deposits will give a higher yield of gold at less cost than heretofore; to provide for greater efficiency in the separation of the gold from the gold bearing "dirt"; and to make possible the operation at a profit of placer gold deposits of relatively low gold content which would ordinarily be regarded as being unprofitable for commercial reclamation for gold.

A further object of my invention is to provide an improved gold reclaiming machine, preferably of a relatively light weight portable nature, which is rugged and which is capable of efficiently handling a large quantity of the gold bearing dirt in a relatively short interval of time.

An additional object of my invention is to provide an improved apparatus for handling and operating on the gold bearing dirt for reclaiming the gold with improved efficiency.

Further objects and advantages of my invention will be more apparent from the following description of one illustrative embodiment of the principles thereof, reference being had to the accompanying drawings in which:

Fig. 1 is a side elevational view of my improved machine.

Fig. 2 is an enlarged sectional elevational view of the main or primary separator portion of my machine.

Fig. 2A is a detail sectional plan view taken along line 2A—2A of Fig. 2.

Fig. 3 is a sectional plan view taken as indicated by line 3—3 of Fig. 1.

Fig. 4 is a detail sectional view taken along line 4—4 of Fig. 3.

Fig. 5 is a further detail sectional view taken transversely of the Fig. 4 structure just below the amalgamating plate.

Fig. 6 is an elevational view of a typical element of the outer separator spiral as seen in Fig. 2.

Fig. 7 is an enlarged sectional view of a portion of one of the Fig. 6 elements, the section being taken as indicated by line 7—7 of Fig. 2.

Fig. 8 is an enlarged sectional elevational view of the secondary separator portion of my machine.

Fig. 9 is an enlarged detail sectional view of a typical part of the secondary separator portion, the view being taken as indicated by line 9—9 of Fig. 8.

In the drawings, I have illustrated my inven-

tion in the preferred form of a portable machine or unit, although it will be understood that stationary units may be employed if desired. This unit comprises a main supporting frame structure A having a fabricated base 10, uprights 11, top 12 and appropriate cross-bracing at 13, 14 and at other desirable locations. Frame A carries support wheels 15, which may be of a type suitable for operation on a track 16.

The gold bearing ore or dirt to be separated is first screened or otherwise treated in a well known manner to bring the dirt down to a pulverized form, water being preferably introduced to the dirt during the screening so that the pulverized dirt will readily flow through a hose 17 to the suction side of a feed pump B, preferably of the centrifugal type for pumping the mixture of water and dirt upwardly through a pipe 18 for discharge into the hopper C. Pump B is operated under power by any suitable prime mover such as the electric motor 19 where a source of electricity is available.

Hopper C is fixed to the upper end of a shaft conduit 20 rotatably supported through a bearing 21 carried by a bracket 22 mounted on the bracing 13. Surrounding shaft 20 and fixed thereto is a bevel gear 23 engaged by a bevel pinion 24 fixed to a drive shaft 25 operated under power, as by the motor 26. The pinion 24 also drives a second bevel gear 27 fixed to the upper end 30 of a hollow shaft 28 surrounding shaft 20 for rotation relative thereto in an opposite direction. The shaft 28 is likewise supported on bracket 22 by a bearing 29.

Fixed at 30 to the lower end of shaft 28 for rotation therewith is the upper housing member 31 which is a part of the outer separator spiral D, the upper end of member 31 being provided with an annular trough 32 adapted to receive a supply of water from one or more supply pipes 33, 34, the water supply being regulated by valves 35.

Drivingly secured to the lower end of shaft conduit 20 is the inner separator spiral E, formed of a double spiral core 36, 37. Each spiral core has a spiral groove 38 in its under face for receiving a spiral water supply pipe 39, each pipe having an upper flexible supply extension 40 leading to a funnel portion 41 of an annular trough 42 supplied with water by pipes 43 and trough 32. The trough 42 is secured to conduit 20 and rotates in one direction therewith while the housing member 31 which is secured to shaft 28 rotates in the opposite direction by reason of a 55

drive received from the bevel pinion 24 to a bevel gear 27 fixed to the upper end of shaft 28.

The cores 36, 37, present a passage below conduit 20 for receiving the material therefrom, this 5 passage progressively tapering downwardly as an inverted cone so that the material discharged from conduit 20 will be progressively caught by the gold separating means carried by the cores as will be presently apparent.

10 Projecting outwardly and downwardly from cores 36, 37 are the rods 45, suitably spaced circumferentially around the cores and threadedly engaging the cores at 45a, for supporting the plates or pans 46, which form a spiral guideway 15 for the dirt. These pans have their inner ends slidably engaged beneath the outwardly projecting ends of core plates 45b secured at 45c to the cores. Plates 45b preferably project inwardly beyond the associated core to catch the material discharged 20 from conduit 20. As a protection against wear, the inner portions of plates 45b may be provided with a hard rubber coating 45d, vulcanized to the upper surface of these plates. Each of the pans 46 has along one side thereof one or more eyelet 25 brackets 47 adapted to readily receive a rod 45, this side being overlapped by the next adjacent pan, thereby providing a continuous outwardly and downwardly extending spiral surface from the cores 36, 37. The pans are held from falling 30 downwardly and outwardly from rods 45 by the abutment screws 48 threadedly engaging the outer ends of the rods, the heads of these screws engaging a bracket 47.

Each of the pans 46 is provided with means 35 for separating and collecting the gold from the dirt as it falls down the pans while washed by the water which was mixed with the dirt entering hopper C and which is added by the spray received from pipes 39, the latter for this purpose having 40 suitable nozzles or openings directed downwardly to wash the dirt as it is introduced to the inner ends of plates 45b. This separating means, in the illustrated embodiment of my invention comprises a plurality of amalgamating plates or 45 ruffles 49 secured to the upper faces of pans 46 and arranged in staggered relationship with one another to baffle the travel of the dirt as it moves downwardly and outwardly of the pans 46.

The pans 46 revolve with spiral E as a part 50 thereof so that the dirt does not fall radially along the pans but rather takes a path intermediate a radial and circumferential travel, the amalgamating plates being preferably arranged to lie across this path of travel. These amalgamating 55 plates are adapted to collect the relatively heavy gold particles while the water washes the dirt over these baffle plates. In order to facilitate the gold separating action, these plates are preferably copper coated with mercury, it being recognized that gold has an affinity for mercury.

Each amalgamating plate 49 is preferably 60 readily attachable and removable to a pan 46 by inserting the inner tongue portion 49a through a pan slot 49b so that the tongue lies beneath the pan with the shank 49c holding the plate 49 in position. Assembly and removal of the plate may be readily accomplished by tilting the plate as will be readily understood. Each plate 49 has 65 a gold collecting pocket formed by the face 49h bounded by upstanding sides 49d and end 49e. The supporting feet 49f preferably disposing the outer edge of the pan substantially parallel to the base of the machine. Each pan may also have one or more gold collecting pockets 49g depressed 70 below the face 49h.

As a further means of holding the overlapped sides of adjacent pans 46 in position during operation of the machine, certain of the plates 49 engage companion slots formed at the overlap, the tongues 49a of such plates serving to connect 5 the adjoining pans 46.

The water supplied to pipes 33, 34 is pumped by a pump 50 through the delivery pipes 51, 52, these pipes having further pairs of supply branches 53, 54 and 55, 56, respectively regulated as to 10 water flowing therethrough by valves 57 and 58 for purposes which will be presently apparent. The supply of water to pump 50 is indicated by a hose 59 preferably flexible to permit the desired degree of movement to the entire machine. 15

The lower end of the spiral E has its cores 36, 37 terminating in a spindle 60 which is recessed at 61 to receive the upper end of a plug 62 which rotatably centers the spiral through a bearing 63. The lower end of the plug is fixed within the 20 upper end of a stationary pipe 64. The plug has a laterally projecting annular flange 65 provided with a pair of diametrically opposite upwardly opening pockets 66 adapted to receive a roller 67 journaled on a pin 68 for rotatably supporting 25 the spiral E at its lower end.

During rotation of spiral E, the latter is preferably vibrated vertically to assist in the separating action of the gold as the dirt is washed over the plates 49. To this end the spindle 60 has 30 an annular cammed face 69 in engagement with rollers 67, the cam faces being arranged to reciprocate or vibrate the spiral. In order to permit this vibration while driving the shaft conduit 20, the latter has a lower shaft portion 70 drivingly connecting shaft 20 with spiral E. The lower end of shaft 20 has an annular series of drive keys 71 slidably fitting the keyways 72 of shaft portion 70, the keyways being open upwardly and being of sufficient length to provide adequate clearance 40 below keys 71 to accommodate the aforesaid movement. 35

Referring now to the outer spiral D, the housing member 31 is formed with a lower annular trough 74 adapted to continuously receive a supply of water from the aforesaid branches 53, 54. 45 This trough has a series of circumferentially spaced downwardly extending outlet pipes 75, each communicating through a flexible detachable hose 76 with a spirally extending pipe 77 secured to 50 the inner wall of a spiral element 78 of the outer spiral D. These elements are contiguously arranged for relative vibration and removal and they together form a cylindrical rotating structure as best shown in Figs. 1 and 2. 55

Each spiral element 78 has an opening 79 at its upper end for supporting such element by a pin 80 of smaller diameter than hole 79 whereby each element 78 may be vibrated as will presently be apparent. The pins 80, which are of any suitable 60 type for convenient removal, are mounted between flanges 81 of the housing member 31 and adjacent spiral elements 78 overlap each other at the stepped engaging sides 82 which preferably have a clearance with each other in an increasing degree toward the lower ends of the spiral elements. 65

Each element 78 has an inwardly projecting spiral trough 83 (see Figs. 6 and 7) arranged below the associated spiral water supply pipe 77 having spray nozzles or holes 84, the floor of each 70 trough 83 having the spaced gold collecting ruffles 85 while the side walls are connected by a series of removable gold collecting elements 86, preferably amalgamating plates generally similar in function to the aforesaid plates 49 of the 75

inner spiral E. In order to increase the gold collecting capacity of these plates, they are formed with a plurality of step-like undercuts 86a, having concave gold collecting pockets 87. These plates are mounted to position, their lower flanges being approximately parallel with the base of the machine.

The spiral elements 78 have their troughs 83 progressively increasing in width in the downward direction and disposed for rotation closely adjacent the outer peripheral edges of the pans 46 to receive the water and dirt thrown from the pans as the latter rotate in the opposite direction. As the dirt washes over the riffles 85 and the amalgamating plates 86 during its travel downwardly in the spiral troughs, gold which escapes collection by the amalgamating plates of the inner spiral is separated and collected by the outer spiral at 85, 86a and 87.

20 While I do not limit my invention to any particular speeds of rotation of the inner and outer separators E and D, where used in combination, I prefer to rotate these separators relatively slowly in equal opposite speeds of about 45 R. P. M. 25 The speed may of course vary according to the quality and quantity of the gold bearing dirt being treated, as well as by reason of other factors.

During rotation of the outer spiral separator D, the elements 78 thereof are preferably relatively vibrated back and forth about the respective axes of pivotal support provided by pins 80, and these elements are additionally vibrated inwardly and outwardly, these vibrations being applied to the lower ends of the spiral elements 35 so that movement at their upper pivoted ends is relatively small. The aforesaid progressively varying clearance will accommodate these relative vibrations between adjacent spiral elements and also facilitate ready outward removal of the 40 spirals for cleaning off and salvaging the gold from the riffles 85 and amalgamating plates 86 by removing pins 80 and permitting each spiral element to slightly drop accompanied by slightly "skewing" the spiral element to clear the adjacent elements.

In order to rotatably center the lower end of the outer spiral D and to impart the aforesaid vibrations to the spiral elements thereof, I have provided the upper end of the stationary drum 50 88 of the secondary spiral separator F with a plurality of idler guide rollers 89 spring pressed at 90. These rollers may be readily outwardly retracted when it is desired to remove or install any or all of the spiral elements 78. Each element 78 has one or more cams 91 formed on its inner face adjacent the lower end thereof, each cam having an inclined face for successive engagement with a plurality of circumferentially spaced rollers 92 rotatably journaled on fixed 60 axes angled parallel with the faces of cams 91. During rotation of the outer spiral D, cams 91 progressively engage rollers 92 to impart the aforesaid compound vibrations to the spiral elements 78.

65 I prefer to provide further means for acting on the material discharged from the lower ends of the spiral troughs 83 although such further means, herein illustrated as comprising the secondary spiral separator F, may be omitted if desired.

The separator F is preferably fixed or non-rotating and comprises a supporting base 93 carried by the base 10 of frame A, this base having a relatively high pitch spirally disposed outer casing 94 terminating upwardly in the aforesaid

drum 88. This casing centrally receives the pipe 64 which extends from base 93 to plug 62 and conducts water supplied thereto through branches 55, 56 for radial discharge to the spray pipes 95 having outlets 96 directed toward the spiral slides 97 (see Figs. 8 and 9).

These spiral slides 97 receive the dirt and water mixture from troughs 83, the dirt falling by gravity down the spiral slides as additional water from pipes 95 is sprayed on the slides. The slides 10 97 are preferably multi-ply burlap which will collect the gold particles as the dirt is washed over and through the burlap. This burlap is removably suspended between casing 94 and pipe 64 by suitable fastening means 98, 99.

15 The casing 94 is supported intermediate its length by a spiral floor 100 extended outwardly from pipe 64, this floor having a series of radially extending gold collecting riffles 101 spaced between stepped amalgamating plates 102 similar 20 to plates 86, the plates 102 being removably mounted between casing 94 and pipe 64 beneath the slides 97 to catch the dirt washed there-through. The pipe 64 thus cooperates with floor 100 and casing 94 to form a spiral gravity dirt 25 conveyor which is trough-like at cross-sections along its length.

If desired, in the interests of conserving the consumption of water, the residue discharged at the bottom of the separator F may be returned 30 to the water pump 50 or to the pump B for re-circulation with the material entering the system at pipe 17 as will be readily understood.

In the operation of the process and machine as a whole, the dirt and water mixture is delivered 35 by pump B to hopper C for discharge downwardly through shaft conduit 20 to the pans 46 of rotating spiral E. This spiral, and also spiral D, preferably rotates in a direction opposite to that experienced with an ordinary spiral drill so 40 that the dirt flow outwardly and downwardly on pans 46 is retarded to facilitate the gold separation and accumulation on plates 49 while washed by water sprayed from pipes 39.

The dirt falling from pans 46 is caught by the 45 spiral troughs 83 of the oppositely rotating outer spiral D, the gold being separated and collected by riffles 85 and plates 86 while the dirt is washed from pipes 71.

During the rotation of the spirals D and E, the 50 material treated thereby is continuously agitated, cams 69 vibrating the spiral E and cams 91 vibrating the spiral elements 78 of spiral D.

The residue discharged from spiral D falls by gravity down and through the burlap slide 97 of 55 the fixed secondary separator F, water sprayed from pipes 95 assisting in the collection of gold by riffles 101 and plates 102.

After the machine has operated a sufficient 60 length of time depending on the gold content of the dirt being treated, the spiral elements 78 are removed for collecting the gold. Convenient access is thereby obtained for removing trays 46 for the same purpose. The burlap 97 is then burned and the gold deposit salvaged while the gold collected by riffles 101 and plates 102 may readily be reached for removal by reason of the height between adjacent turns of the open spiral F. The parts are then again assembled with new burlap 70 97, and the separating process repeated.

The gold may be readily removed from the amalgamating plates in any suitable and convenient manner as by brushing the plates in the presence of water, the mercury, which will ordi- 75

narily largely brush off also, being distilled for reclamation.

Instead of using water during the gold reclaiming process in the machine, as hereinbefore set forth, I may employ other forms of fluid such as compressed air to facilitate the separation of gold in a dry pulverized dirt mixture, assisted if desired by magnetic riffles.

Various changes in the details of construction and operation of my machine and in the mode of carrying out my process will be readily apparent from my disclosure of the principles of my invention, as set forth in the claims appended hereto, and I do not limit my invention to such details and specific process hereinbefore described.

I claim:

1. Gold reclaiming apparatus comprising a rotatable separator structure having its axis disposed substantially vertically, means for rotating said separator structure about said axis, said separator structure having an axial spiral core providing a dirt conducting passage, means for introducing gold-bearing dirt to the upper end of said core for gravity flow downwardly therethrough, the convolutions of said spiral core being spaced from each other to provide dirt passage laterally therebetween, said convolutions progressively diminishing in diameter from the upper end portion of said core toward the lower end portion thereof to catch said dirt flowing downwardly therethrough, a spiral guideway extending laterally of said core for conducting said dirt laterally outwardly from said spaces between the convolutions of said spiral core, and gold collecting means carried by said guideway.

2. A gold separator comprising a spiral core forming a vertically disposed passageway having lateral openings between the convolutions of said spiral core, means for introducing gold-bearing dirt to the upper end of said core passageway for gravity flow downwardly therethrough and laterally through said openings, a spiral guideway carried by said core for conducting said dirt generally outwardly from said core openings, and gold collecting means carried by said spiral guideway.

3. A gold separator comprising a spiral core having a vertically disposed passageway open laterally between the convolutions of said spiral core, means for introducing gold-bearing dirt to the upper end of said core passageway for conducting said dirt generally outwardly from between said core convolutions, gold collecting means carried by said spiral guideway, and means for rotating said core and spiral guideway as a unit.

4. A gold separator comprising a spiral core forming a vertically disposed passageway having lateral openings between the convolutions of said spiral core, means for introducing gold-bearing dirt to the upper end of said core passageway for gravity flow downwardly therethrough and laterally through said openings, a spiral guideway carried by said core for conducting said dirt generally outwardly from said core openings, gold collecting means carried by said spiral guideway, and a pipe carried by said spiral core, said pipe being spirally wound adjacent the inner edges of the convolutions of said spiral guideway for directing a fluid toward said spiral guideway to facilitate gold collection by said gold collecting means.

5. Gold reclaiming apparatus comprising a separator structure having its axis disposed substantially vertically, said separator structure hav-

ing an axial core providing a dirt conducting passage, means for introducing gold-bearing dirt to the upper end of said core passage for gravity flow downwardly therethrough, said separator structure further including a spirally disposed guideway extending outwardly from and around said core for conducting said dirt generally laterally outwardly from said core passage, said spiral guideway comprising a plurality of pan sectors, support members underlying said spiral guideway and projecting laterally outwardly and downwardly from said core to support said pan sectors, said support members being spirally spaced from each other and secured at their inner ends to said core, and gold collecting means carried by said pans.

6. Gold reclaiming apparatus comprising a separator structure having its axis disposed substantially vertically, said separator structure having an axial core providing a dirt conducting passage, means for introducing gold-bearing dirt to the upper end of said core passage for gravity flow downwardly therethrough, said separator structure further including a spirally disposed guideway extending outwardly from and around said core for conducting said dirt generally laterally outwardly from said core passage, said spiral guideway comprising a plurality of pan sectors, a plurality of support rods underlying said spiral guideway and projecting laterally and outwardly and downwardly from said core, said support members being spirally spaced from each other and secured at their inner ends to said core, each of said pan sectors having one of its outwardly extending edge portions overlying one of said support rods and having the other of its outwardly extending edge portions overlapping and supported by the rod-supported edge portion of an adjacent pan sector, and gold collecting means carried by said pans.

7. A gold separator comprising a spiral core forming a vertically disposed passageway having lateral openings between the convolutions of said spiral core, means for introducing gold-bearing dirt to the upper end of said core passageway for gravity flow downwardly therethrough and laterally through said openings, a spiral guideway carried by said core for conducting said dirt generally outwardly from said core openings, and gold collecting means carried by said spiral guideway, said spiral core being tapered to progressively position successive convolutions thereof inwardly of said passageway to catch the dirt flowing downwardly in said passageway.

8. In a gold separator, a plurality of contiguous spiral elements together forming a substantially cylindrical housing structure having its axis disposed vertically, means carried by the inner wall of each of said spiral elements for collecting gold, means disposed within said housing structure for conducting gold-bearing dirt to each of said spiral elements substantially throughout the lengths thereof, and means for rotating said cylindrical housing structure about said axis during said conduction of the dirt to said spiral elements.

9. In a gold separator, a plurality of contiguous spiral elements together forming a substantially cylindrical housing structure having its axis disposed vertically, means carried by and disposed inwardly of each of said spiral elements for collecting gold, means disposed within said housing structure for conducting gold-bearing dirt to each of said spiral elements substantially throughout the lengths thereof, and means for

- pivotally supporting said spiral elements for swinging movement thereof relatively to each other.
10. In a gold separator, a plurality of contiguous spiral elements together forming a substantially cylindrical housing structure having its axis disposed vertically, means for pivotally supporting the upper end of each of said spiral elements for swinging movement relative to each other, means carried by the inner wall of each of said spiral elements for collecting gold, means disposed within said housing structure for conducting gold-bearing dirt to each of said spiral elements substantially throughout the lengths thereof, of, an annular water storage trough disposed at the upper end of said cylindrical housing structure, a spiral pipe carried by the inner wall of each of said spiral elements for directing water toward the dirt conducted to said elements, and 20 a flexible water conducting conduit between each of said spiral pipes and said trough adapted to supply water from said trough to said spiral pipes while accommodating said swinging movement of said spiral elements relative to said trough.
- 25 11. In a gold separator, a substantially spiral rotatable guideway having its axis extending substantially vertically, means for conducting gold-bearing dirt vertically downwardly along said axis for distribution laterally thereof to the 30 convolutions of said guideway at points spaced along said axis, means for rotating said guideway, a plurality of recessed amalgamating plates carried by the upper faces of said spiral guideway and spaced from each other to baffle the 35 dirt during passageway thereof on said spiral guideway from said axis to the outer edges of the convolutions of said spiral guideway.
12. Gold reclaiming apparatus comprising a separator structure having its axis disposed substantially vertically, said separator structure having an axial core providing a dirt conducting passage, means for introducing gold-bearing dirt to the upper end of said core passage for gravity flow downwardly therethrough, said separator 40 structure further including a spirally disposed guideway extending outwardly from and around said core, said core having openings for distributing the dirt to said guideway at points substantially throughout the length of said core passage, said spiral guideway having a slope which extends in a direction radially outwardly and downwardly from said core passage and which has sufficient inclination to cause the dirt to flow by gravity radially of said core passage and circumferentially thereof along a spiral path for gravity 45 discharge from the outer edges of said spiral guideway substantially throughout the length thereof, and gold collecting means carried by said guideway.
- 50 13. In a gold separating apparatus, an inner separator having a spiral dirt guideway sloping radially outwardly and downwardly, means for conducting gold-bearing dirt to said guideway, an outer separator having a spiral dirt guideway, the convolutions of which are disposed to position the inner periphery thereof adjacent the outer periphery of the convolutions of the inner spiral guideway to receive dirt from the latter convolutions substantially throughout the length thereof, 55 the convolutions of the outer separator having a relatively greater inclination than that of the convolutions of the inner spiral, and gold separating means carried by said guideways.
14. In a gold separating apparatus, an inner 60 separator having a spiral dirt guideway, means for conducting gold-bearing dirt to said guideway, an outer separator having a spiral dirt guideway, the convolutions of which are disposed adjacent the outer periphery of the convolutions of the inner spiral guideway substantially throughout the length thereof to receive dirt outwardly from the convolutions of the first said guideway, gold separating means carried by said guideways, and a spirally wound fluid conducting pipe for each of said separators respectively adapted to direct fluid under pressure toward said spiral guideways.
- 65 15. In a gold separating apparatus, an inner separator having a spiral dirt guideway sloping radially outwardly and downwardly, means for conducting gold-bearing dirt to said guideway, an outer separator having a spiral dirt guideway, the convolutions of which are disposed adjacent the outer periphery of the convolutions of the inner spiral guideway substantially throughout the length thereof to receive dirt outwardly from the convolutions of the first said guideway, and gold separating means carried by said guideways, the convolutions of said spirals extending in opposite directions relative to each other.
- 70 16. In a gold separating apparatus, an inner rotatable separator having a spiral dirt guideway sloping radially outwardly and downwardly, means for conducting gold-bearing dirt to said guideway, an outer rotatable separator having a spiral dirt guideway, the convolutions of which are disposed adjacent the outer periphery of the convolutions of the inner spiral guideway substantially throughout the length thereof to receive dirt outwardly from the convolutions of the first said guideway, gold separating means carried by said guideways, means drivingly connecting said inner and outer separators for simultaneous rotation thereof in opposite directions, a third nonrotatable separator disposed below 75 said outer separator for receiving dirt therefrom, means for rotatably supporting the lower end of said inner separator on the upper end of said third separator, and gold collecting means associated with said third separator.
- 80 17. In a gold separating apparatus, an inner rotatable separator having a spiral dirt guideway sloping radially outwardly and downwardly, means for conducting gold-bearing dirt to said guideway, an outer rotatable separator having a spiral dirt guideway, the convolutions of which are disposed adjacent the outer periphery of the convolutions of the inner spiral guideway substantially throughout the length thereof to receive dirt outwardly from the convolutions of the first said guideway, gold collecting means carried by said guideways, means for simultaneously rotating said separators in opposite directions, a third nonrotatable separator having a spiral dirt guideway adapted to receive dirt from one of the first said separators, means for journaling the lower end of said inner separator on said third separator, gold collecting means carried by said third separator, and means for directing fluid toward said guideways during passage of the dirt therealong.
- 85 18. In a gold separating apparatus, an inner separator having a spiral dirt guideway sloping radially outwardly and downwardly, means for conducting gold-bearing dirt to said guideway, an outer separator having a spiral dirt guideway, the convolutions of which are disposed adjacent the outer periphery of the convolutions of the inner spiral guideway substantially throughout the length thereof to receive dirt outwardly from the convolutions of the first said guideway, gold separating means carried by said guideways, and a spirally wound fluid conducting pipe for each of said separators respectively adapted to direct fluid under pressure toward said spiral guideways.

19. In an ore separator, a spiral core having an axial dirt passageway, a plurality of rods having their inner ends attached to said core, said rods being spaced from each other along the length 5 of said core and sloping downwardly and outwardly therefrom, a plurality of contiguous pan sectors together forming a spiral dirt guideway, and means removably supporting said pan sectors on said rods.
- 10 20. In a gold separator, a substantially spiral trough-like conveyor adapted to convey gold-bearing dirt by gravity from the upper end of said conveyor to the lower end thereof, gold separating means extending across said trough-like conveyor at a plurality of points along the spiral 15 length thereof for collecting gold from said dirt, a spirally disposed filter forming a cover for said trough-like conveyor, means for introducing gold-bearing dirt to the upper end of said filter for gravity passage along the spiral length thereof 20 and for passage therethrough to said gold separating means, a fluid-conducting pipe extending vertically along the axis of said spiral conveyor, branch pipes radiating from said vertically extending pipe at points along the length thereof 25 for directing fluid toward said spiral filter, and means for introducing fluid under pressure to said vertically extending pipe.
21. In a gold separator, upright spirally extending passage forming means for conducting gold-bearing dirt by gravity downwardly therethrough, said passage forming means having its spiral convolutions spaced from each other to form a substantially spirally extending opening, 30 means for conducting said dirt in a series of superimposed spiral paths extending laterally outwardly and downwardly from said spirally ex- 35
- tending opening, and gold collecting means carried by said laterally extending dirt conducting means.
22. In a gold separator, upright spirally extending passage forming means for conducting gold-bearing dirt by gravity downwardly therethrough, said passage forming means having its spiral convolutions spaced from each other to form a substantially spirally extending opening, 5 means for conducting said dirt in a series of superimposed spiral paths extending laterally outwardly and downwardly from said spirally extending opening, said passage forming means having its spiral convolutions progressively inwardly offset to catch the dirt conducted downwardly therethrough for passage through said spirally extending opening, and gold collecting means carried by said laterally extending dirt conducting means.
23. In a gold separating apparatus, an inner 20 vertically disposed separator having an inner spiral dirt guideway sloping downwardly and outwardly for gravity flow of gold-bearing dirt, the convolutions of said inner guideway extending for substantially more than 360°, means for conducting said dirt to said inner guideway, an outer vertically disposed separator having an outer spiral dirt guideway adapted to receive said dirt from along the periphery of the convolutions of said inner guideway, the convolutions of said outer guideway extending for substantially less than 360° but for substantially the height of said convolutions of said inner guideway, and means for rotating said separators simultaneously in opposite directions.

FRANK W. BRINTNALL.
